UNITED STATES PATENT OFFICE.

WILLIAM W. HOFFMAN AND FRANCIS W. POWERS, OF LAFAYETTE,
INDIANA.

AUTOMATIC RAILWAY-SWITCH.

SPECIFICATION forming part of Letters Patent No. 664,750, dated December 25, 1900.

Application filed April 19, 1900. Serial No. 13,563. (No model.)

To all whom it may concern.

Be it known that we, WILLIAM W. HOFFMAN and FRANCIS W. POWERS, citizens of the United States, residing at West Lafayette, in the county of Tippecanoe and State of Indiana, have invented certain new and useful Improvements in Automatic Railway-Switches; and we do hereby declare the following to be a full, clear, and exact description of the invention, such as will enable others skilled in the art to which it appertains to make and use the same.

Our invention relates to improvements in railway-switches, and particularly to that class of switches designed to be operated by devices carried upon a locomotive or car.

Our invention further relates particularly to that class of switches in which the points of the switch-rails move vertically rather than laterally.

Our invention has for its object to produce certain improvements in railway-switches of this character heretofore used; and it consists in the novel features hereinafter described and claimed.

Our invention will be understood by reference to the drawings, wherein the same parts are indicated by the same letters throughout the several views.

Figure 1 is a top plan view of a railway-switch and connections constructed according to our invention. Fig. 2 is a sectional side view taken on the line 2-2 in Fig. 1 with switch set for main track and looking in the direction of the arrow. Fig. 3 is a section taken on the line 2-2 in Fig. 1 with switch set for side track and looking in the direction of the arrow. Fig. 4 is a top plan view of the switch when constructed to be used only as a hand-switch. Fig. 5 is a view of the switch as seen when it is boxed up, as it is designed to be. Fig. 6 is a section taken at right angles to the sections shown in Figs. 2 and 3 on the line 6-6 in Fig. 1 looking in the direction of the arrow and on a larger scale, the switch-points being set for the siding. Fig. 7 is a sectional view similar to Fig. 6, showing the switch-points as set for the main track. Fig. 8 is a detail perspective view of the switch-target and operating connections between the target and the switch mechanism. Fig. 9 is a detail per-

spective view of one of the transverse cranked shafts through which the switch mechanism is operated by means of devices on the locomotive through plates on the track engaging cranks on the said shaft. Fig. 10 is a perspective view of one of the rock-shafts which support the vertically-movable switch-points, the particular rock-shaft shown in this figure having radial pins thereon, such as are used nearest the ends of the said switch-points. Fig. 11 is a detail view, in vertical section, through the axle of the locomotive, showing in elevation the devices for engaging the switch-operating devices on the track, showing both of the slot-controlled wheels elevated. Fig. 12 is a view similar to Fig. 11, showing one of the slot-controlled wheels in operative position, the dotted lines in this figure indicating the position of the other of said slot-controlled wheels elevated. Fig. 13 is a side view showing one of the pivoted plates which are fixed upon the ties between the rail and over the inner cranks on the switch-operating shafts, together with its inclosing guide frame or case; also, its connections with the shaft and cranks of the unlocking device. These particular pivoted plates are such as are near the points of switch-rails, the plate being in its horizontal position. Fig. 14 is a perspective view of one of the bearing-plates constituting a support for the end of one of the rock-shafts shown in Fig. 10. Fig. 15 is a perspective view of another form of bearing-plate. Fig. 16 is a diagrammatic view from a point in front of the locomotive, showing the manner in which the locomotive attachment engages the pivoted plates of the switch-gear. Fig. 17 is a view similar to Fig. 13, showing the pivoted plate depressed. Fig. 18 is a similar view of one of the pivoted plates at the other end of the switch about to be engaged by the depressing-wheel on the locomotive. Fig. 19 is a detail view of a section of the rock-shaft E², showing the device to prevent a rebound of the switch when thrown very suddenly. Fig. 20 is a top detail view of a section of one of the switch-points, designed particularly to show the stop or lug u, which prevents the switch-point from being raised too high. Referring particularly to Fig. 1, A repre-

sents the cross-ties, which rest upon longitudinal sills A'. There are two of these sills A', one arranged along each of the straight-track rails, and the said track-rails are mounted upon the cross-ties and secured thereto by spikes or in any other preferred well-known manner.

One of the main-track rails B is continuous, while the other one of the main-track rails B' turns off at b' to form one of the rails of the siding, and the other section of this rail B² is connected to one of the switch-points C', by means of which the train is directed to the siding or to the main track, as the case may be, as will be hereinafter more fully described. As above stated, one of the main-track rails turns off to form one of the siding-rails, as shown at C², and the other siding-rail C³ terminates adjacent to the main-track rail B in the other switch-point C. The flanges of the rails B and B' are cut away along their inner sides, as seen in Figs. 6 and 7, and the switch-points C and C' are beveled or tapered along their sides adjacent to these track-rails, so as to fit closely thereto, as will also be seen in Figs. 6 and 7. The switch-points C and C' are connected by pin-joint, as shown at c and c', so as to permit of a vertical pivotal movement of the said switch-points.

30 D, D', and D² represent a series of rock-shafts which are mounted transversely of the track and are journaled at their ends on one side of the track in a set of blocks D³, (shown in Fig. 15,) mounted upon one sill A', and are journaled at their opposite ends in a set of supporting-blocks D⁴, (shown in Fig. 14,) which blocks are mounted upon the other sill A'.

Where the lower flanges of the fixed rails are cut away upon the inner sides thereof, it will be impracticable to use spikes, that are generally used. So we provide metal chairs B^a. (Seen most clearly in Figs. 6 and 7.) These chairs are bolted upon the outer side of the rails and also extend beneath the rail, so as to make a solid seat therefor, besides being secured by bolts or spikes upon the ties. Both of these sets of blocks are spiked to the sills A'. The blocks D⁴ at one side of the track have preferably each an open-slot d' in its vertical flange instead of an opening similar to the opening d³ in the blocks D³ and are fitted with detachable plates d⁴, arranged to hold rock-shafts securely in position when bolted down, but to allow of the removal of any one of said bars when worn or for any other reason by detaching the plate. Each of the said rock-shafts is provided with a pair of enlargements D⁶ and D⁷, set at an angle of ninety degrees to each other, as seen most clearly in Fig. 10. These enlargements D⁶ and D⁷ are arranged to lie immediately beneath the switch-points C and C' and when turned by turning of the rock-shafts to a horizontal position are arranged to lie upon the plates supporting the ends of the said rock-shafts. This arrangement is such as to cause all the enlargements, such as D⁶, beneath one of the

switch-points C to lie flat upon the plates D⁴, while the enlargements D⁷, which lie beneath the other switch-point C', occupy a vertical position beneath the said switch-point C'. The effect, as will be readily understood, is to elevate one switch-point to a level with the tread of its adjacent main-track rail, while the other switch-point lies at an inclination, with its end beneath the other and corresponding rail sufficiently below the tread thereof to avoid the possibility of the flanges on the locomotive or car wheels striking the depressed switch-point. Inasmuch as each switch-point has a downward inclination from its pivotal connection with the corresponding rail, it will be obvious that some provision will be necessary to allow this inclination and yet at the same time provide a good support for the switch-points. This we accomplish by having the supporting-blocks D³ and D⁴, in which or upon which the ends of the rock-shafts D, D', and D² are journaled, of gradual decreasing thickness from the pivotal connection of the switch-points toward the ends thereof, as will be seen most clearly in Fig. 3, wherein are seen only the blocks D⁴; but it should be understood that the same applies to the set of blocks D³ beneath the switch-point C'.

In order to allow the requisite movement to the switch-points, the ties beneath the same must necessarily be cut away to a depth sufficient to allow the switch-points to fall to their lowest positions allowed by the blocks D³ and D⁴. Further, it is necessary to make up the difference in the distance of vertical movement of the various portions of the switch-point, and we accordingly provide the rock-shafts with supporting-blocks D⁶ and D⁷ of gradual increasing thickness as the supporting-blocks become thinner. Thus it will be seen that while all the rock-shafts rotate together the graduation in thickness of the enlargements of the said rock-shafts corresponds with the distance to be traveled by the corresponding portion of the switch-point, so that when the latter has been raised to its elevated position on a level with the tread of the main-track rail the corresponding enlargements upon the rock-shafts provide good supports therefor, and it will also be seen that the graduation in thickness of the supporting-blocks D³ and D⁴ permit of the necessary drop to the switch-points. It will be understood that it is only necessary that the ends of the switch-points should be dropped out of the way of the flanges of the wheels.

In order to hold the ends of the switch-points firmly against the main-track rails, we preferably provide a flat spring-plate B⁴, secured to the inner side of the track-rail and overlapping the switch-points, so that the latter will be held closely against the inner side of the track-rail under ordinary conditions. This spring-plate, however, will permit of a slight displacement of the switch-point by the flanges of the wheels of the car running backward from the siding to the main track when

the switch is set for the main track or running backward through the switch on the main track when the switch-points are set for the siding, thus avoiding the liability of derailment of the car.

In order to insure the falling of the switch-point at the proper time should its weight not be sufficient under any conditions, we provide upon each switch-point near the end an inwardly-extending lug or bracket C^1 , arranged to be struck by a pin or stud D^8 upon the corresponding supporting-block D^6 or D^7 of the rock-shaft D , which is the nearest to the ends of the said switch-points. A rock-shaft of this construction is shown in Fig. 10, to which reference is had for a clearer understanding of this feature. The remaining rock-shafts D' and D^2 need not be provided with any device for causing the depression of the switch-points, as the above-described device operated by the rock-shaft at the point where the greatest leverage, and therefore the least power, is necessary will be sufficient.

Each of the switch-points is provided with a stop or lug u , which will be best understood by referring to Fig. 20, in which a section of the adjacent main rail is cut away for the purpose of showing the stop. It consists of an iron lug or bracket u , firmly bolted or otherwise fastened to the under side of the switch-point C and extends underneath the main-track rail B , so as to prevent the switch-point C from being raised above the level of the tread of the main track B . It is to be understood that the other switch-point C' is furnished with the same kind of a device. The lugs are shaped so as to present a sharp edge upward and also downward, so nothing will lodge on the top of it to prevent the switch-point being raised. This feature is best shown in Figs. 2 and 3.

Each of the rock-shafts D , D' , and D^2 is provided at one end with a crank-arm—such as d^6 , d^6 , and d^7 —such crank-arm being arranged at an angle midway between the angles of the enlargements D^6 and D^7 upon the said rock-shafts, and to these cranks is connected a connecting-rod D^9 , the connections being so arranged that a longitudinal movement of the said connecting-rod D^9 will rotate the three rock-shafts and through an equal angle. The connecting-rods D^{10} and D^{11} , as seen most clearly in Fig. 1, extend in opposite directions along the outside of the track some distance and pivotally connect this series of cranks to the cranks e' and e^2 on the rock-shafts E' and E^2 , by which said connecting-rods D^{10} and D^{11} , and through them the rock-shafts D , D' , and D^2 , are operated from a locomotive, as hereinafter described. The rock-shafts E' and E^2 are journaled in bearing brackets or sills E^3 and E^4 between the track-rails, and each of these rock-shafts E' and E^2 is provided with a pair of cranks E^5 and E^6 , set at an angle of one hundred and eighty degrees to each other and fitted with rollers e^5 and e^6 as bearing-surfaces. These

cranks E^5 and E^6 are so arranged that they lie at equal angles upon opposite sides of the crank e' or e^2 , as the case may be, and above 70 these cranks E^5 and E^6 are arranged vertically-swinging bevel-plates F , these said plates being each pivotally mounted at one end in a casing F' , (shown in detail in Fig. 13,) which casings are secured upon the cross-ties A between the track-rails and immediately over the said cranks upon the operating rock-shafts. As will be seen in the drawings, there are two sets of these vertically-swinging plates F , and there are two of these in each 80 set. One of such plates F in each set is arranged immediately over one crank E^5 on the operating-shaft, while the other of such plates is arranged immediately over the other crank E^6 on the same shaft. By this arrangement 85 when the appropriate one of the plates F is depressed upon its corresponding crank on the operating rock-shaft the latter is given a partial rotation, and through it and its connections the rock-shafts D , D' , and D^2 are 90 operated. After one shifting of the switch-points in this manner the other plate of this set or of the other set must be depressed upon the corresponding crank on the operating rock-shaft, which through its connections 95 shifts the switch-points to their original positions. The provision of these plates between the track-rails and the cranked operating-shafts E' and E^2 is to afford means for the throwing of the switch by the engineer 100 on a moving train.

In Figs. 11, 12, and 16 we have shown devices to be carried upon the front axle of a locomotive under the control of the engineer for throwing the switch as desired. These 105 devices consist of a wrist H^3 on the front axle of the locomotive. From this wrist and extending upward is an arm H^3 , which is connected by a rod H^4 to a lever H^5 in the cab of the locomotive, as shown in Fig. 11. Extending downward from the wrist H^3 are two pairs of plates H and H' . (See Fig. 16.) These plates are parallel to each other, perpendicular to the axle, and are rigid with the said wrist H^3 . In each plate is an eccentric slot. 115 The slot in one plate of each pair is made to coincide with the slot in its mate; but the eccentric in one pair of plates is just the reverse of the eccentric of the other pair. Between each pair of plates is pivoted a wheel 120 on an axle h^5 , which extends through the slots in the plates. A rod H^6 is attached to the axle of the wheel h^5 and another rod H^7 is attached to the axle of the wheel h' . The other end of each rod is pivoted to the pilot-frame in 125 front at h^6 . These rods will allow the wheels h^5 and h' to move up and down, but not backward or forward. Now when the engineer wishes to throw the switch for the side track he can throw his lever H^5 backward to the 130 notch s , as in Fig. 12, and, as will be seen, the slotted plates will be swung forward, so that the slots h^5 will force the wheel h' down, so as to depress the pivoted plate F down on the

- crank e^6 beneath it, which will cause the shaft E^2 or E^6 to rotate, which, as has been explained, will throw the switch for the side track by elevating the switch-point C and depressing the other switch-point C' . The wheel h^2 will be elevated, as in Fig. 16, by that part of the slot h^4 that is nearest the car-axle being brought directly underneath the said car or locomotive axle. It will readily be understood that moving the lever H^5 forward to the notch s^3 the arm H^3 will be moved forward and the slotted plates will be swung backward, so the slot h^3 will elevate the wheel h^2 , while the slot h^4 will be in such a position as to hold the wheel h^2 down, so as to engage the other pivoted plate F and rotate the rock-shafts in opposite direction, which will throw the switch for the main track by depressing the switch-point C and elevating the other switch-point C' . It is shown in Fig. 11 that when the arm H^3 stands directly above the axle, as will be the case when the lever H^5 is moved to an intermediate notch, as at s' , the pairs of slotted plates will both be in such a position as to elevate both wheels, in which position it is designed to be at all times, only when used to throw a switch.
- It will be seen by referring to Fig. 16 that the attachment to the locomotive is placed near the right side of the locomotive looking forward, and the pivoted plates F , in the switch-gear, that are to be used from a locomotive going in one direction, are placed accordingly near the right side of the track looking forward from the moving train. It will also be understood that the attachments on the locomotive cannot engage the same pivoted plates when running in the opposite direction.
- By having the pivoted plates F provided with a long inclination or bevel, as shown, the injurious effects of shocks caused by the sudden striking of any one of these plates by the mechanism of the locomotive is avoided.
- In order to cause the plates to return to their upward position after being depressed, we preferably provide very strong springs f . (Seen in Figs. 13, 17, and 18.)
- The switch may be used as a hand-switch by extending one of the operating rock-shafts, such as D , (see Fig. 4,) into the extension E^8 , which is provided with a crank e^8 and is connected to a semaphore or target E^9 .
- To lock the rock-shaft E^2 against turning, we provide thereon a pair of radial lugs or projections e^9 and e^{10} , arranged to be engaged in a notch k' on the pivoted spring-controlled arm K . When the switch is closed, or, in other words, set for the main track, as shown in Figs. 2 and 8, the lug or projection e^{10} on the shaft E^2 is engaged by the notch k' on the spring-controlled arm K , as seen most clearly in Fig. 8; but when the switch is opened or turned for the siding the lug or projection e^9 on the shaft E^2 would engage the notch k' on the spring-controlled arm K .

It should be understood that the switch

mechanism and all the connections, except those of the hand-operating mechanism and the edges of the pivoted plates F , will in practice be boarded over or otherwise suitably closed, as shown in Fig. 5, so as to exclude ice or snow and to prevent tampering with the mechanism by any person unauthorized to do so.

The switch is automatically unlocked by a device consisting of a double crank-shaft N on bearings N^5 , as seen in Fig. 8, and the other end on bearings bolted to the under side of the casing F' , as will be seen most clearly at N^4 in Figs. 13 and 17. The cranks N^1 and N^2 are fitted with rollers to lessen the friction against the downward points F^2 , as shown in Figs. 13 and 17, when either one of the pivoted plates F is pressed down. The down-point F^2 engages the crank N^1 or N^2 , as the case may be, and throws the cranks on that shaft through their full sweep, so that the crank N^3 will raise the spring-controlled arm K , which releases the lug e^9 or e^{10} , as the case may be, from the notch k' , and thus the switch is unlocked before the pivoted plate F touches the crank E^5 or E^6 on the shaft E^2 . Then as the pivoted plate F is pressed further down it engages the crank E^5 or E^6 beneath it and throws the switch, when the other lug e^9 or e^{10} is caught in the notch k' and the switch is securely locked again. A similar device is at the other end of the switch, as is shown in Figs. 1 and 18, the shaft M with its cranks M^1 and M^2 , to be engaged by the down-point F^3 , which acts similar to the one at the other end of the switch just described, only the down-point engages the crank M^1 or M^2 in such a way as to turn the crank M^3 downward, and the said crank M^3 engages the crank M^4 on the long shaft M^5 , which lies in bearings fastened to the ties on the outside of the main track, as will be seen in Fig. 1. This long shaft terminates in a crank M^6 under the spring-controlled arm K . The downward pressure of crank M^3 on the crank M^4 causes the shaft M^5 to rotate enough to cause the crank M^6 to raise the spring-controlled arm K and release the lug e^9 or e^{10} , as the case may be, as in the other case the lug e^9 or e^{10} is released before the crank that throws the switch is engaged by the pivoted plate F ; but as the plate F is pressed further down on the crank beneath it throws the switch.

A device, as shown in Fig. 19, is provided to prevent a rebound of the switch when thrown by a train running at a great speed. It consists of a roller v' , with bearings projecting from the crank-shaft E^2 and in line with the crank e^2 . A horizontal-bar spring is bolted to the sill A' and projects over the top of said roller v' , pressing it downward, which, it will be understood, tends to hold the shaft E^2 to its extreme limit whichever way it is thrown. It will be seen that by making the spring v sufficiently strong the locking device might be dispensed with in some

switches, where by their location they would not need to be locked against unauthorized persons.

In order to permit of the switch being unlocked by hand, we preferably provide, in addition to the mechanism just described, a rod O, having thereon a lug or crank o, arranged beneath the end of the catch-arm K, so that when the rod is in one position, as shown in Fig. 8, the switch remains locked; but upon its being turned the lug o, engaging beneath the catch-arm, causes the latter to become disengaged. A drop-lever is pivotally attached to the target-shaft, by which the switch may be thrown. Inasmuch as the rod O will in practice be boarded over or otherwise covered in order that this unlocking by hand may be accomplished, this rod O is provided with an upwardly-extending arm O' at its end next the semaphore, which arm O' extends upwardly through the covering in position for being operated by hand. The said arm may be locked, so as to throw it out of use, by engagement with a catch or retaining device O², such as is actually used upon railroads in connection with switch-operating levers and the like.

Having thus described our invention, what we claim, and desire to secure by Letters Patent of the United States, is—

1. In a railway-switch, the combination with pivoted switch-points having vertical movement, supports for the said switch-points arranged to elevate the one switch-point while the other is depressed, a lug on each of the said switch-points, a projection on one of the supports for each, arranged to strike said lug and insure the depression of the corresponding switch-point at the proper time, and connections between the said supports for simultaneously operating the series; of a cross-shaft having a crank thereon connected to the supports of the switch-points, and having cranks thereon between the rails of the track; and pivoted plates located between the rails of the track in positions for operating said cranks when depressed, substantially as described.

2. In a railway-switch, the combination with pivoted switch-points having vertical movement, supports for the said switch-points arranged to elevate the one switch-point while the other is depressed, a lug on each of the said switch-points, a projection on one of the supports for each, arranged to strike said lug and insure the depression of the corresponding switch-point at the proper time, and connections between the said supports for simultaneously operating the series; of a cross-shaft having a crank thereon connected to the supports of the switch-points, and having cranks thereon between the rails of the track; pivoted plates located between the rails of the track in positions for operating said cranks when depressed, and means for locking the switch-points in either adjustment, substantially as described.

3. In a railway-switch, the combination with pivoted switch-points having vertical movement, supports for the said switch-points arranged to elevate the one switch-point while the other is depressed, a lug on each of the said switch-points, a projection on one of the supports for each, arranged to strike said lug and insure the depression of the corresponding switch-point at the proper time, and connections between the said supports for simultaneously operating the series; of a cross-shaft having a crank thereon connected to the supports of the switch-points, and having cranks thereon between the rails of the track; pivoted plates located between the rails of the track in positions for operating said cranks when depressed, means for automatically locking the switch-points in either adjustment, and means for automatically unlocking the switch operated by the said pivoted plates, substantially as described.

4. In a railway-switch, the combination with vertically-movable switch-points, supports for the said switch-points arranged to elevate the one and depress the other alternately, connections between the said supports for operating the same simultaneously, and devices upon the track arranged to be operated by an attachment upon the locomotive for operating said supports; of spring-guides fixed to main-track rails, and bearing upon the inner faces of the said switch-points to hold the latter normally close against the sides of the rails, but to permit of their displacement by the flange of a car-wheel entering from the rear of the switch-point, substantially as described.

5. In an automatic railway-switch, the combination with pivoted switch-points, of a series of cross-shafts D, D' and D² mounted transversely of the track, and having supporting-blocks set at angles to each other for elevating and depressing the switch-points; fixed journal-blocks for the ends of said shafts; said journal-blocks forming supports for both the switch-points and the said shafts, and one set of said journal-blocks having a detachable journal-plate to permit of the disengagement of said shaft; cranks on the said shafts and connections between the said cranks; of devices located upon the track arranged to be operated by a mechanism upon the locomotive for rocking said shafts and operating the switch-points, substantially as described.

6. In an automatic railway-switch, the combination with pivoted plates having a long inclination, arranged upon the track; rock-shafts having cranks located beneath the said pivoted plates in position to be borne upon thereby, when said plates are depressed, and a spring for returning each of said plates to its elevated position after being depressed; of connections between the said rock-shafts and the switch-points for operating the latter upon the depression of one of said pivoted plates upon its corresponding crank on said rock-shaft, substantially as described.

7. In an automatic railway-switch, the combination with the ties of the track, of sills under the said ties, bearing-plates mounted upon the said sills, rock-shafts journaled in the said bearing-plates and provided with integral enlargements for elevating and supporting the switch-points successively; of pivoted switch-points having vertical movement; lugs projecting laterally from the said switch-points, projections on one of the said rock-shafts arranged to engage said lugs when turned to depress a switch-point, spring-guides for retaining the ends of the said switch-points in close relation with the sides of the track-rails; and means arranged to be operated by devices upon the locomotive, for rocking the said rock-shafts, substantially as described.
8. In an automatic railway-switch, the combination with the switch-points and devices for operating the same, a rock-shaft connected with such devices arranged to be actuated by devices upon the locomotive; of projections set at angles upon the said rock-shaft, a spring-operated catch arranged to engage one of said projections at a time, and a series of rock-shafts arranged when operated to disengage the said catch, and so release the switch mechanism, substantially as described.
9. In an automatic railway-switch, the combination with the switch-points and devices for operating the same, a rock-shaft connected with such devices arranged to be actuated by devices upon the locomotive; of a projection set at angles upon the said rock-shaft, a spring-operated catch arranged to engage one of said projections at a time, a series of rock-shafts actuated by the switch-operating mechanism from the locomotive to disengage the said catch and so release said mechanism, substantially as described.
10. In a switch-operating device for moving vehicles, the combination with a rigid swinging arm fixed to a wrist on the axle of said vehicle, a connecting-rod for operating said swinging arm, of two pairs of slotted plates rigidly connected to said wrist, and with rollers or wheels hung between said plates; rods pivotally connected to the journals of each of said wheels, and each of said rods having a separate stationary pivotal connection, substantially as described.
11. In a switch-operating device for moving vehicles, the combination with a rigid swinging arm on a wrist, a connecting-rod for operating said swinging arm; of two pairs of eccentrically-slotted plates rigidly connected to said wrist, rollers carried in between said slotted plates, rods pivotally connected to the journals of each of said rollers, and each of said rods having a separate stationary pivotal connection, substantially as described.
12. In a railway-switch, the combination with pivoted switch-points having vertical movement, supports for the said switch-points arranged to elevate the one switch-point while the other is depressed, a lug on each of the said switch-points, a projection on one of the supports for each, arranged to strike said lug; and insure the depression of the corresponding switch-point at the proper time, connections between the said supports for simultaneously operating the series, and a lug or stop fixed to each of the switch-points projecting under the main-track rail; of a cross-shaft having a crank thereon connected to the supports of the switch-points, and having cranks thereon between the rails of the track; and pivoted plates located between the rails of the track in positions for operating said cranks when depressed, substantially as described.
13. In an automatic railway-switch, the combination with the switch-points and devices for operating the same; a rock-shaft connected with such devices arranged to be actuated by devices upon the locomotive; of projections set at angles upon the said rock-shaft, a spring-operated catch arranged to engage one of said projections at a time, a series of rock-shafts arranged when operated to disengage said catch, and so release the switch mechanism, a projection on said rock-shaft; and a flat spring *v* making frictional contact therewith, substantially as described.
14. In an automatic railway-switch, the combination with the switch-points, devices for operating the same; a rock-shaft connected with such devices arranged to be actuated by devices upon a locomotive; of projections set at angles upon said rock-shaft; a spring-operated catch arranged to engage said projections and a series of rock-shafts arranged when operated to disengage the said catch and so release the switch mechanism, a shaft on bearings with a lug arranged under said spring-catch, and with upturned arm to be locked by key to semaphore, to be unlocked by authorized persons, and a drop-lever pivoted to the upright shaft of the semaphore to be used as means for unlocking and operating the switch by hand; an operating-shaft on bearings having supporting-blocks arranged under the switch-points for the purpose of raising and lowering the same; the shaft extended and provided with a crank connected to a semaphore of ordinary design to be operated by hand as a hand-switch, all substantially as described.

In testimony whereof we affix our signatures in presence of two witnesses.

WILLIAM W. HOFFMAN.
FRANCIS W. POWERS.
